UNITED STATES PATENT OFFICE.

HENRY L. LEWIS, OF STRATFORD, CONNECTICUT.

APPARATUS FOR DUMPING AND THROWING OYSTER-DREDGES.

1,169,548.

Specification of Letters Patent. Patented Jan. 25, 1916.

Application filed March 8, 1915. Serial No. 12,818.

To all whom it may concern:

Be it known that I, HENRY L. LEWIS, a citizen of the United States, residing at Stratford, county of Fairfield, State of Connecticut, have invented an Improvement in Apparatus for Dumping and Throwing Oyster-Dredges, of which the following is a specification.

This invention has for its object to provide simple, strong and durable apparatus for dumping and throwing oyster dredges, which shall wholly eliminate manual labor both in dumping and throwing a dredge. It is of course well understood that dredges are ordinarily drawn on board the boat by power and are dumped by hand, which requires two strong men, and are then lifted by the men and thrown overboard.

In order that the operation of dumping and throwing dredges may be performed wholly mechanically, I have devised the novel apparatus which I will now describe, referring to the accompanying drawings forming a part of this specification, and using reference characters to indicate the several parts.

Figure 1 is an elevation of my novel apparatus in its normal position on a boat, as seen from the outer side; Fig. 2 a side elevation of the apparatus as seen from the right in Fig. 1, and also showing the samson post, so called, on an oyster boat; Fig. 3 a similar elevation showing the position of the apparatus after a dredge has been drawn up and the apparatus has commenced to tilt to dump the dredge; Fig. 4 a similar view showing the position of the apparatus in dumping the dredge, and Fig. 5 is a perspective of the dredge adapted for use in connection with my novel apparatus.

10 denotes a dredge which may be of any ordinary or preferred construction, the only requirements to adapt it for use with my novel apparatus being that the club, so called, of the dredge, which is indicated by 11, be long enough to engage the apparatus, and that the arms 12 of the dredge be provided with suitable projections 13 which must also engage the apparatus. The 45 dredge chain, indicated by 14, passes over a pulley 15 on the samson post 16, and is wound by power on a drum, not shown, as it forms no portion of the present invention.

The side of the boat is provided with a table 17, shown in dotted lines only, and at the

outer edge of the table is a horizontal roller 18 mounted in brackets 20 and 21 secured to the table. Bracket 21 is provided with an extension 22 on which a substantially vertical roller 23 is mounted. In drawing a dredge, the chain passes over roller 23 until the dredge is disengaged from the bottom, when, as the samson post is located centrally with relation to roller 18, the chain will swing to a substantially vertical position 65 and will pass over roller 18. These parts are all in common use, but are referred to as they coöperate with my novel apparatus.

The invention comprises essentially a swinging carrying frame and dumping means. The frame comprises arms 24 which are pivoted at substantially their mid-length and a plate 25 secured to the arms which is adapted to support the dredge and in the normal position of the apparatus rests 75 against and protects the side of the boat, as shown in Fig. 2. The lower portions of the arms preferably diverge for convenience in handling a dredge and above their pivotal points the arms are preferably bent inward 80 for ease and quickness in operation. The upper ends of the arms lie in substantial alignment with the lower portions and are provided with outwardly extending hubs 26 to which dumping levers 27 are pivoted. 85 These levers are provided with inwardly offset projections 28 and with undercut shoulders 29. Blocks 35 secured to the edge of the table serve as rests for the levers in their normal position and as fulcrums on which 90 the levers swing during the first portion of the dumping operation (see Fig. 3).

30 denotes links pivoted to the projections and having shoulders 31 adapted to be engaged by the projections on the dredge, and 95 yokes 32 which inclose the upper portions of the arms and slide freely thereon.

The operation is as follows: In drawing a dredge, as soon as it swings free from the bottom, the chain will lie centrally or nearly so of roller 18 and the nose of the dredge will follow it over the roller. The dredge will be drawn upward until projections 13 on the arms of the dredge engage shoulders 31 on the links. The club of the dredge will 100 now have passed over the lower ends of the dumping levers and the bag will be resting against the supporting plate. Continued pull upon the chain, owing to the engagement of the projections on the dredge with 105 110

the shoulders on the links, will cause the apparatus to tilt, carrying the dredge with it, as clearly shown in Fig. 3. As the tilting operation proceeds, the club of the dredge 5 will drop down into engagement with the shoulders 29 on the levers. It will be noted that, in the direction of movement of the dredge, the pivotal points of the levers to the arms lie forward of the lower point of 10 attachment of the bag of the dredge to the frame. When the parts reach substantially the position shown in Fig. 4, the bottom of the dredge bag will be jerked taut and the movement of the levers stopped, the effect of 15 which is to cause the contents of the bag to be expelled and to drop out upon the deck of the boat, 33 (see dotted lines) indicating the position of the frame and 34 the position of the bag. As soon as the dredge is 20 dumped, the chain is allowed to pay out and the apparatus tilts backward, past the position indicated in Fig. 3, until it reaches its normal position, as in Fig. 2, the dredge sliding freely off from the plate, the operations of dumping and throwing being 25 performed entirely without manual labor.

Having thus described my invention I claim:—

1. Apparatus of the character described comprising a swinging dredge-carrying frame, levers pivoted to the frame and links pivoted to the levers and provided with yokes which engage and slide on the frame and with shoulders adapted to be engaged 30 by a dredge, whereby the apparatus is tilted and then the levers are swung upward to dump the dredge.

2. Apparatus of the character described comprising a swinging dredge-carrying frame and pivoted means carried thereby and adapted to be engaged by a dredge, and links for causing said pivoted means to swing the dredge into dumping position when the dredge-carrying frame is swung 40 inward.

3. Apparatus of the character described comprising a swinging dredge-carrying frame, levers adapted to be engaged by a dredge and pivoted to the frame, and links 50 also adapted to be engaged by a dredge and pivoted to the levers and having sliding engagement with the frame.

4. Apparatus of the character described comprising a swinging dredge-carrying frame, levers pivoted to the frame and having shoulders adapted to be engaged by the club of a dredge and links pivoted to the levers and provided with yokes which engage and slide on the frame and with shoulders adapted to be engaged by the frame of 55 a dredge.

5. Apparatus of the character described comprising a swinging dredge-carrying frame, levers pivoted to the frame and having shoulders near their lower ends adapted 60

to be engaged by the club of a dredge and links pivoted to the levers and offset therefrom, said links being provided with yokes adapted to engage and slide on the frame and with shoulders adapted to be engaged by a dredge, so that when a dredge is drawn 70 into engagement with the shoulders the apparatus will tilt, the levers will be swung upward, the club of the dredge will engage the shoulders and the contents of the dredge 75 will be dumped.

6. Apparatus of the character described comprising swinging arms adapted to be pivoted at substantially their mid-length, the upper portions of said arms being bent 80 backward, and the upper ends in substantial alinement with the lower portions, levers pivoted to the upper ends of the arms and having shoulders near their lower ends for engagement by the club of a dredge, and 85 links pivoted to the levers and off-set therefrom and provided with yokes which slide on the arms and with shoulders adapted to be engaged by a dredge frame.

7. Apparatus of the character described comprising arms pivoted at substantially their mid-length and provided at their upper ends with outwardly extending hubs, levers pivoted to the hubs and having inwardly extending projections near their upper ends and shoulders near their lower ends adapted to be engaged by the club of a dredge, blocks against which the levers are adapted to rest at substantially their mid-length, and links pivoted to the projections 90 and provided with yokes which slide on the arms and with shoulders adapted to be engaged by a dredge frame.

8. In combination, a boat, a swinging dredge-carrying frame secured thereto and adapted to be engaged by a dredge to cause 105 said frame to be swung inward, levers pivoted to the frame, and connections between the levers and the frame which are engaged by the dredge to cause the levers to dump the dredge after it has been swung inward on the frame, the dredge being thrown, by the return of the parts to normal position, when released.

9. In combination, a boat, a swinging dredge-carrying frame pivoted thereto, a dredge, levers pivoted to the frame and adapted to be engaged by the dredge, links pivoted to the levers and having sliding engagement with the frame and adapted to be engaged by the dredge and a power-operated chain attached to the dredge, whereby the latter is dumped and thrown without 110 manual labor.

10. In combination, a boat, a dredge comprising a bag, a dredge-carrying frame secured to the boat and adapted to swing inward and levers and links carried by the frame and engaged by the dredge, whereby 115 inward movement of the dredge upon the 120 bag will cause the dredge to be dumped and thrown without manual labor.

frame will cause the bag to be swung upward by the dumping means and jerked taut to expel the contents.

11. In combination, a boat, a dredge, a swinging dredge carrying frame pivoted to the boat, dumping means pivoted to the frame forward of the point of attachment of the dredge bag to the dredge frame and adapted to be engaged by the dredge, and a power operated chain attached to the dredge, whereby the bottom of the dredge is swung upward and the bottom jerked taut to expel the contents.

12. In combination, a boat, a swinging

dredge-carrying frame, levers pivoted to 15 the frame and links pivoted to the levers and having sliding engagement with the frame and adapted to be engaged by a dredge simultaneously with the swinging movement of the carrying frame to swing the levers 20 and bottom of the dredge upward.

In testimony whereof I affix my signature in presence of two witnesses.

HENRY L. LEWIS.
